UNITED STATES PATENT OFFICE.

WILLIAM J. DOYLE, OF CINCINNATI, OHIO, ASSIGNOR TO THE MONITOR STOVE AND RANGE COMPANY, OF CINCINNATI, OHIO, A CORPORATION OF OHIO.

HINGE FOR MOLDERS' FLASKS.

1,102,573.

Specification of Letters Patent.

Patented July 7, 1914.

Application filed April 15, 1912. Serial No. 690,818.

To all whom it may concern:

Be it known that I, WILLIAM J. DOYLE, a citizen of the United States, residing at Cincinnati, in the county of Hamilton and 5 State of Ohio, have invented certain new and useful Improvements in Hinges for Molders' Flasks, of which the following is a specification.

My invention relates to hinges for molders' flasks in which a match-plate is employed, and it has for its object the provision of new and improved means whereby the match-plate is accurately positioned with relation to the flask; further, whereby 10 by the pattern on the face-side of the match-plate may be molded in the drag, and the match-plate, after the drag has been turned, then partially raised, the mold provided with a suitable surfacing powder, and the 15 match-plate then accurately returned to original position for the purpose of reprinting; and further, whereby the match-plate may be readily removed upon only partial raising of the cope, the cope being then 20 swung back into mating relation with the drag so that the molded portions in each will register accurately with each other.

It is a further object of my invention to so construct the hinge that the movements 25 of the match-plate and cope will take place in such manner as to cause accurate registry of the match-plate and of the molded parts with relation to the other.

The invention will be further readily 30 understood from the following description and claims, and from the drawings, in which latter:

Figure 1 is a perspective view of a flask with a match-plate between the cope and 35 drag, the cope being in partly raised position, this partly raised position being sufficient to permit the removal of the match-plate, the latter being shown in inclined seated position in full lines, and in dotted 40 lines to show the clearance provided between the cope and drag for removal of the same upon only slight raising of the drag. Fig. 2 is a side elevation showing the hinge, the drag, match-plate and cope being partly 45 broken away, the parts being shown in closed relation. Fig. 3 is a similar view of the same with the cope in partly raised relation. Fig. 4 is a side elevation of the 50 same, with the cope and drag in closed relation and the match-plate removed. Fig.

5 is a bottom perspective view of the cope-member of the hinge. Fig. 6 is a top perspective view of the match-plate member of the hinge. Fig. 7 is a bottom perspective view of the match-plate member of the 60 hinge. Fig. 8 is a top perspective view of the drag-member of the hinge. Fig. 9 is a vertical axial section taken on the line 9—9 of Fig. 2. Fig. 10 is a cross-section of my improved device corresponding to the line 65 10—10 of Fig. 9. Fig. 11 is a vertical section taken on the line 11—11 of Fig. 2; and, Fig. 12 is a plan view of the drag-member of the hinge.

11 represents the cope and 12 the drag of 70 a molder's flask, between which a match-plate 13 is arranged to be received. This match-plate has on its face-side 14, the face of the pattern which is to be molded. In practice the face-side is usually molded 75 while the drag is in inverted position, whereupon the drag is provided with a bottom or follow-board and the drag reversed for bringing the match-plate at the top of the drag. The cope is then placed 80 upon the match-plate and provided with molding sand which is then suitably pressed into the cope against the back-face 15 of the match-plate. It is of course obvious that the molding in the drag and cope 85 may take place simultaneously by pressure or otherwise, depending on the system of molding employed.

For suitably positioning the match-plate and permitting its movement with relation 90 to the drag and cope and for suitably positioning the cope with relation to the match-plate and drag, I provide novel hinge mechanism which I shall now describe. The pivotal sides of the drag, match-plate and 95 cope are provided at a plurality of points, preferably near the ends of said sides, with hinges 16, 16. Each of the hinges is provided with a drag member 17, a match-plate member 18, and a cope-member 19. The 100 drag-member is suitably secured to the drag of the flask. It is provided with a plurality of hinging points, one of which is applicable to the match-plate member and the other of which is applicable to the cope-member of the hinge, these hinging points being in separated parallel vertical planes, arranged at different distances with relation to the drag. The match-plate member 105 is provided with spaced-apart bearing-disks 110

21 having a trunnion 22 therebetween provided intermediate of its ends with an interruption 23. The inner faces 24 of the disks are preferably formed sloping.

5 I have shown the butt 25 of the match-plate member of the hinge secured to the match-plate with the upper and lower faces of the butt coincident with the upper and lower faces of the match-plate, but the 10 match-plate member of the hinge may if desired be made integral with the match-plate.

The drag-member is provided with spaced-apart bearing recesses 28 for the bearing-disks 21 and a channel 29 for the 15 trunnion 22. The side walls 30 of the bearing-recesses, slope to match the sloping inner faces 24 of the bearing-disks. The drag-member comprises a rearward extension 31 in which there is a bearing-slot 32 at the sides of which there are sloping walls 33 forming clearance recesses 34 in rear of the channel and connecting with the channel by depressions 35, forming sand clearance spaces for the channel. The interruption 23 forms a clearance-space between the 20 trunnions 22 and channel 29, and the rear edge 36 of the match-plate member at said interruption forms a wiper for any sand which may be lodged in said channel. The 25 drag-member is shown suitably secured to the drag, as by means of a butt 37 and a tail-piece 38.

The cope-member is provided with bearing-recesses 41 which coact with the bearing-disks 21. These bearing-recesses are 30 spaced apart. This spaced-apart construction gives great rigidity to the individual hinges. It also comprises a rearward extension 42 having a pivot-pin 43 thereon, at 35 the ends of which outwardly sloping lateral bearing-faces 44 are provided, there being an opening 45 in said cope-member forward of said pivot-pin through which the front upwardly extending wall 46 of the slot-bearing 32 is received. The rear wall 47 of said bearing-slot is preferably higher than the front wall thereof. The cope-member is provided with suitable means for securing the same to the cope, as by means 40 of a butt 48 and a tail-piece 49.

The axis of the bearing-disks of the match-plate member is located in the plane of the lower face of the match-plate when extended, and the bearing-recesses 28 are 50 substantially a half-circle for receiving the downwardly projecting portions of said bearing-disks for providing a large bearing surface for the match-plate member when swinging the match-plate upon the drag. 55 The form of the trunnion and the interruption therein and the sloping mating faces between the bearing-disks and bearing-recesses provide means whereby sand is cleared from the hinge.

60 In order to accurately locate the cope with

relation to the match-plate, the cope-member is also provided with bearing-recesses 41, on which the cope swings when lowered adjacent to the match-plate, so as to accurately position the cope with relation to the match-plate. My improved hinge also permits the match-plate to be removed upon only slight raising of the cope. Upon a slight raising of the cope, the pivotal bearing thereof is transferred from the bearing-disks 21 to the slot and pin pivot 32, 43, and upon such transference and a slight further raising of the cope at an angle of approximately forty degrees, the match-plate is readily removed, as indicated in 70 dotted lines in Fig. 1. My improved construction further permits the match-plate to be raised upon its bearing-disks for facing the face-side of the mold with a suitable surfacing powder, my improved construction being such as to insure accurate return of the match-plate by again lowering the same upon the drag for accurately reprinting the pattern of the face of the match-plate into the surfaced mold in the drag. 75

80 My improved construction further insures the accurate positioning and matching of the cope-portion of the mold with the drag-portion thereof, by swinging the cope upon the pivot-pins 43 resting upon the bottoms 90 of the bearing-slots 32, the axes of these pivot-pins being in the plane of the upper surface of the drag and the lower surface of the cope. The axis of the pivot-pin 43 is located in a vertical plane which is parallel to but separated from the vertical plane of the axis of the bearing-disks 21. 95

100 Having thus fully described my invention, what I claim as new and desire to secure by Letters Patent, is:

1. A flask-hinge comprising a drag-member, a cope-member, and a match-plate member, the said match-plate member comprising spaced-apart bearing-disks having peripheral bearing surfaces and a trunnion therebetween of substantially less diameter than said bearing-disks, said drag-member provided with spaced-apart bearing-recesses for said bearing-disks, and the said trunnion and drag-member provided with a sand-clearance recess located between said bearing-disks when said hinge is assembled. 110

115 2. A flask-hinge comprising a drag-member, a cope-member, and a match-plate member, the said match-plate member comprising spaced-apart bearing-disks and a trunnion therebetween of substantially less diameter than said bearing-disks, the said drag-member provided with spaced-apart bearing-recesses for said bearing-disks, an intermediate channel for said trunnion and in rear thereof with a bearing-slot having sloping recesses at the sides thereof connecting with said channel forming sand-clearance connections therebetween, and said 120 125 130

cope-member provided with a pivot-pin for said bearing-slot.

3. A flask-hinge comprising a drag-member, a cope-member, and a match-plate member, the said match-plate member comprising spaced-apart bearing-disks and a trunnion therebetween of substantially less diameters than said bearing-disks, the said drag-member provided with spaced-apart bearing-recesses for said bearing-disks and a channel between said bearing-recesses for

said trunnion, said trunnion provided with an intermediate interruption forming a sand-clearance space in said channel.

In testimony whereof, I have hereunto 15 signed my name in the presence of two subscribing witnesses.

WILLIAM J. DOYLE.
